UNITED STATES PATENT OFFICE.

JOHN STIRLING, OF GRABOW, LOUISIANA.

PLOW ATTACHMENT.

1,313,611.

Specification of Letters Patent.

Patented Aug. 19, 1919.

Application filed March 19, 1918. Serial No. 223,320.

To all whom it may concern:

Be it known that I, JOHN STIRLING, a citizen of the United States, residing at Grabow and State of Louisiana, have invented 5 certain new and useful Improvements in Plow Attachments, of which the following is a specification.

The invention has for an object to provide an improvement in plow constructions 10 serving to take the place of the sole plate ordinarily provided on plows, which it is well understood by agriculturists after repeated plowing of a field, produces a hardened stratum of earth which greatly obstructs 15 permeation of the soil by water, and also limits the penetration of crop roots, all of which have detrimental effects. With the use of my device no packing of the soil beneath the plow need occur, as would happen 20 with the ordinary plow having a sole base, and there will also be less frictional resistance to the forward movement of the plow.

It is also a purpose of the invention to effect desirable improvements in the specific 25 construction and mounting of such an appliance, enabling the production of a steel faced wheel device at a low cost, using but a small quantity of steel, yet retaining the advantage of a heavy wheel body of cast metal 30 such as iron.

A further aim is to improve the functioning of the device in having a steering effect upon the plow tending to keep it upon a straight line during forward movement, as 35 will appear.

Additional objects, advantages, and features of invention will appear from the construction, arrangement and combination of the parts as particularly described herein- 40 after, and shown in the drawings, wherein,

Figure 1 is a detail view of the appliance upon a plow.

Fig. 2 is a cross sectional view of the wheel.

Fig. 3 is a plan view of a blank for the wheel element.

Fig. 4 is an enlarged detail of the mounting of the fork.

There is illustrated a plow comprising a 50 stock element 10, upon the forward part of which there is mounted a plow point and mold board 11 which may be stamped integrally from one piece of sheet metal, and extending rearwardly from the stock 10 55 there is a wheel mounting 12 carrying a wheel 13 having a sharpened edge portion,

the sides of which are inclined toward each other at an acute angle, so that the body portion of the wheel intermediately of the axis and periphery is extremely narrow, it being 60 the intention that the wheel shall sink considerably in the sub-soil behind the plow, whereby twisting or turning of the plow will be resisted by the wheel, which itself cannot readily be turned on a vertical axis 65 when embedded as indicated in the drawings.

The wheel mounting consists of a fork element having parallel arms, in the outer ends of which there is fixed a shaft 14 engaged through the wheel, and the mounting 12 is bolted to the stock in a suitable manner. The head portion of the fork is suitably apertured to receive a bolt 15 engaged therethrough and through the stock 10, and 75 the bolt 15 may be a part of the means utilized for holding the plow 11 to the stock 10. The head of the fork may also have a set screw 16 engaged therethrough, to impinge against a washer 17 confined between 80 the head of the fork and the back side of the stock 10, the washer having portions turned outwardly beside the stock 10 to prevent it from turning, and the set screw serving to prevent the fork from turning upon 85 the bolt.

In Fig. 4, there is indicated a construction in which the fork element is formed of two parts, including the side arms 12', having upper inturned portions 18 which are extended from stem portions 19 extending longitudinally therefrom in a plane parallel to the arms 12' and securely bolted together. The stem portions have outer forward parts bent laterally at right angles thereto in a 95 common plane to form attaching flanges 20, extending outwardly into the plane of the arms 12'. A clamping plate 21 is provided, having an area equal to the combined area of the two flanges 20, and the plate 21, and 100 the flanges 20 and head portion 18 are provided with registered openings at each side, those in the flanges 20 being threaded, and receiving therein threaded bolts 22, which are slidably engaged through the plate 21 and head portions 18. Between the head portions 18 and flanges 20 suitable nuts 23 are engaged upon the bolts movable to bear against the head portions 18 as will be subsequently described for adjustment of the 110 support arms with relation to the longitudinal axis of the plow to which the device is

attached. Suitable nuts 24 are also provided at the outer ends of the bolts 22 whereby the plate 21 may be borne toward the flanges 20 to clamp an interposed plow stock, 5 for mounting of the appliance.

The wheel element may be formed in various ways, but preferably comprises two opposed slightly dished steel disks 25, having their edges suitably beveled toward 10 their recessed sides, in order that the disks may be brought together snugly in alinement, to form a sharp edge. The disks are centrally apertured and the immediately adjacent portions around the apertures are 15 pressed inwardly in a cylindrical form, and trimmed with the ends of the cylindrical portions in a plane with the edge portions of the respective disks, so that when the disks are brought together, the cylindrical portions 20 abut snugly to form a continuous passage through the wheel. A plurality of irregularly shaped tongues 27 are pressed inwardly from the material of the disks outwardly of the skein portions 26, projecting 25 inwardly at an oblique angle to the adjacent portions of the disk, and to the medial plane of the wheel. The space between the disks is filled with any cheap metal, such as cast iron, and it would be possible to use iron 30 with a large part of slag therein, the slag having the effect of forming a cellular structure in the body of the wheel, the purpose of the filling being merely to give body and rigidity to the wheel, so that the use of such 35 material as mentioned is quite satisfactory. In the production of the wheel, any approved method for supporting the disk element within a mold while introducing the filling metal may be followed.

40 In the use of the appliance, the wheel being assembled in the fork as described, the fork is secured upon the stock of the plow in such position that the periphery of the wheel at its lower part extends a short distance below the plow, the relative height of 45 the wheel to the plow, however, being determined by the depth at which it is desired that the plow shall operate, to a considerable extent. By reason of the thinness of the 50 wheel, and its sharpened edges, it sinks to a considerable depth in the soil beneath the plow, whereby it exerts a steering effect upon the plow, causing the plow to follow a line in its forward movement nearly or

quite corresponding with the medial plane 55 of the wheel, or in a line representing the results of the lateral forces acting upon the plow, and the wheel, but having a markedly steadyng effect upon the plow, preventing abrupt deviation from the path desired, and 60 obviating much of the labor required on the part of the plowman in pulling the plow handles first one way and then the other to counteract the effect of small bodies of soil of differing density or compactness, stones, 65 clods, and inequalities of surface.

With the last described form of device, after it is secured upon the plow stock, it may be found that with the style of plow employed and the position of the wheel as 70 first attached, the plow tends to follow a line at an angle to the path traveled by the tractive means, which may comprise an animal or mechanical tractor, in which case, either the handles of the plow would have 75 to be constantly thrown to one side or the other, to counteract this tendency, or other means provided for giving the plow a directional adjustment, ordinarily. However, by means of the nuts 23, described, loosening 80 thereof at one side and tightening thereof against the head portion 18 at the opposite side will adjust the wheel in the angular relation of its major plane to the longitudinal axis of the plow to rectify the error 85 in its directional function.

What is claimed:

1. In a device of the character described, a wheel comprising two dished sheet steel disks having central portions pressed inwardly to form abutting cylindrical skein elements and having meeting peripheral edge portions, and a filling of base metal. 90
2. In a device of the character described, a wheel comprising dished sheet steel disks 95 having central portions pressed inwardly to form cylindrical skein elements and having meeting peripheral edge portions and a filling of base metal, said disks having tongues struck in therefrom, said base metal being 100 cast between the disks and around said tongues.

In testimony whereof I have affixed my signature in presence of two witnesses.

JOHN STIRLING.
